UNITED STATES PATENT OFFICE.

JOSEPH E. HOLMES, OF CUSHING, OKLAHOMA.

PROCESS OF AND APPARATUS FOR PRODUCING LIGHT HYDROCARBONS.

1,241,979.

Specification of Letters Patent.

Patented Oct. 2, 1917.

Application filed August 31, 1915. Serial No. 48,318.

To all whom it may concern:

Be it known that I, JOSEPH E. HOLMES, a citizen of the United States, residing at Cushing, in the county of Payne and State 5 of Oklahoma, have invented new and useful Improvements in Processes of and Apparatus for Producing Light Hydrocarbons, of which the following is a specification.

My invention relates to a process of and 10 apparatus for producing gasoline and naphtha from petroleum oil and petroleum oil distillates, such as kerosene, gas oil and wax oil.

One object of the invention is to provide 15 a method and apparatus which will yield a larger amount of gasoline or naphtha from a given amount of petroleum oil or petroleum oil distillate than is possible with ordinary processes and apparatus.

Another object is to provide a process and 20 apparatus for carrying out and completing the production of gasoline and kerosene in a single continuous operation.

Still another object of the invention is to 25 provide an economical process and apparatus, and one that will effect a thorough separation of the lighter oils from the heavier products and produce a superior quality of kerosene.

In the drawings hereto annexed, and 30 forming a part of this specification,—

Figure 1 is an elevational view of the apparatus.

Fig. 2 is a diagrammatic view, partly in 35 elevation and partly in section, of the same.

Fig. 3 is a vertical section through the expansion drum.

Fig. 4 is a sectional plan view of the same.

In the practical carrying out of the present invention, I provide a primary retort or heater 1, heated from a suitable furnace 2, and embodying a coil of pipe of suitable length and diameter. Connected with the terminals of this coil are conducting pipes 40 3 and 4. The intake pipe 3 serves as a combined conducting and mixing conduit, in which the petroleum oil or petroleum oil distillate employed is commingled with natural gas, the oil and gas being forced 45 through the pipe 3 to the coil 1 by means of suitable pumps 5 and 6, a meter 7 being provided in the intake pipe for indicating the amount of the oil pumped to the coil, and suitable gages 8 being arranged in the 50 branches of said pipe leading from the re-

spective pumps for indicating the pressures of the oil and gas.

The mixture of oil and gas forced into the coil 1, in the ratio of two volumes of gas to one volume of oil, is subjected therein, 60 while under comparatively high pressure, to a comparatively high temperature, all the lighter volatiles being thereby vaporized in the coil and placed under high tension and pressure. In practice, the pressure in the 65 retort 1 is varied from 50 to 100 pounds per square inch depending on the temperature, which is maintained at from 750 to 1100 degrees Fahr., depending on the density of the oil to be cracked.

From the coil the vapors and gas discharge through the outlet pipe 4 and pass to an expansion and separator drum 9, a pyrometer 10 and a gage 11 being provided in the pipe 4 to indicate the temperature 75 and pressure, while also in said pipe is provided a pressure regulator 12, by means of which the pressure of the vapor and gas flowing to the expansion drum may be governed and the pressure and tension of the 80 vapor and gas within the drum regulated to any desired degree.

The drum 9 comprises a cylindrical vessel having at its top an inlet 13 with which the pipe 4 is connected, and an outlet 14, 85 and having at its bottom a drain pipe 15 having a controlling valve 16 therein, which pipe may form part of a pumping line, for forcing the heavier products into any suitable receiver. The inlet 13 and outlet 14 are separated by a vertically disposed baffle 17, whereby the vapor and gas entering the expansion drum are caused to pass downwardly into said drum and are prevented from taking a direct outlet through the outlet or discharge connection. The vapor and gases passing into the drum are thereby caused to expand under adiabatic conditions and are thereby relieved of compression, thus allowing the heavier constituents to 100 condense and precipitating the tar, coke and other heavier products which may be discharged through the pipe 16, while the lighter and more volatile constituents and gas remain in a vaporous and gaseous state, 105 owing to their high temperature, and discharge through the outlet 14.

As stated, the pressure in the retort 1 may vary from 50 to 100 pounds per square inch and the temperature from 750 degrees to 110

- 1100 degrees Fahr., dependent upon the density of the oil to be cracked. The temperature and pressure maintained by direct heat will at all times be such, with relation 5 to the specific gravity of the oil under treatment, as to effect a thorough continuation of the vaporizable portions of the oil with the gas, and such also as to place the mixture in such conditions that when raised to 10 a higher temperature and pressure, it will be adapted for adiabatic expansion to precipitate all of the heavy constituents. This higher temperature and pressure is secured by the use of the pressure regulator 12, which 15 confines the mixture in the retort, by establishing a resistance to its discharge, whereby the mixture is kept confined until heated to a degree higher than that required for the intimate mixture of its components. As a 20 result the pressure of the mixture will also be raised until its temperature and pressure reach the proper stages to place the mixture in condition for adiabatic expansion, at which time the pressure of the mixture will be sufficient to overcome the resistance of the regulator 12 and the mixture 25 will discharge from the retort and enter and expand adiabatically within the expansion drum.
- 30 The vapors and gas discharge through the outlet 14 pass through a pipe 18 to a primary condensing coil 19 arranged within a suitably cooled condensing box or chamber 20, in which coil the vapors are condensed, 35 as will be readily understood. From the coil 19, the condensate and gas pass into a separator 21, in which the noncondensable gas is separated from the condensate, the condensate discharging through a pipe 22 40 containing a controlling valve 23, while the gas discharges through a pipe 24 having a controlling valve 25, through which pipe the gas may be conducted to any suitable point. In the present instance, the pipe 24 is shown 45 as leading back to the retort furnace 2 for the purpose of utilizing the gas as a fuel agent for heating purposes.
- The pipe 22 leads to a pair of secondary stills 26 and 27 and is provided with valves 50 28 and 29 for controlling the flow of the condensate to the respective stills. As shown, the stills 26 and 27 may be arranged within and heated from a common furnace 30, which may be of any preferred type, and the stills 55 28 and 29 may be provided with a common drain pipe 31 having a draw-off valve or cock 32, whereby the heavier particles or any residue remaining therein after distillation may be discharged and provision made for cleaning 60 out the stills whenever required. Arranged within the condenser box or casing 20 are secondary condensers 33 and 34, the condenser 33 being connected with the still 26 through a valved vapor conducting pipe 35, 65 while the still 27 is connected with the con-

denser 34 through a valved conducting pipe 36, in which condensers the gasoline and kerosene vapors will be respectively condensed. The gasoline and kerosene vapors thus condensed in the coils 33 and 34, may 7 be discharged through discharge pipes 37 and 38 to a receiving house or point 39 and thence into tanks or other receptacles 40 and 41 in which the finished gasoline and kerosene are stored. It will, of course, be understood that the condensate from the separator 21 may first be distilled in the still 26, and the gasoline condensed in the condenser 33, and that the residuum from the still 26 may then be conducted into the still 27 to distil 80 off the kerosene, which may be condensed in the condenser 34.

It will be seen that my improved process provides for the commingling with the oil or distillate under treatment of natural gas, 85 which contains a proportion of gasoline capable of being liberated under adiabatic compression, and that by the use of this gas the mixture when heated will be vaporized under high tension and pressure. As a result, the molecules of matter composing the oil are more thoroughly broken, thus changing their atomic weights and by reason of the great expansion of the mixture more 90 efficiently separating the fine solid carbonaceous matter, with a result that there is a greater separation of the molecules forming the lighter hydrocarbons, such as naphtha, gasoline and kerosene, resulting in a much 95 greater yield of the substances. Furthermore, 100 by separating these liquids by adiabatic pressure, a more complete separation of the lighter hydrocarbons from the heavier products will be affected. It will, of course, be understood that in this process all of the 105 condensate from the separator may be conducted to both secondary stills and the gasoline and kerosene vapors separated and successively distilled off and condensed, and that after the oil has been once treated, if 110 it should be desired not to make any kerosene, the remaining oil after the gasoline has been primarily taken off can be repeatedly put through the process until nothing 115 remains but tar and gasoline. In this process a peculiar cracking of the oil is effected, as set forth owing to the great expansibility of the gas when heated and the capability of the petroleum oil to absorb gas when mixed therewith and introduced and treated in the 120 retort 1 under high pressure and temperature. The gas, by reason of its expansibility, keeps the retort 1 full at all times and keeps the oil moving to the surface of the coil pipe. Under such conditions in the retort 1 no opportunity is afforded for the tar and sand to stop and adhere to the pipe, which would 125 cause the oil to scorch and burn and leave an objectionable odor with the oil after passing through the retort. One objection to

cracked oils is their disagreeable odor and the obstruction to the retort when the sediment and tar are allowed to stick to the retort, and burn into a hard scale or cake. 5 By treating the oil in the presence of gas I eliminate the bad odor and increase the life of the retort in an obvious manner.

I claim:—

1. An apparatus for producing gasoline 10 or other like light hydrocarbons from a petroleum oil or distillate comprising a retort, means for supplying measured quantities of a petroleum oil or distillate and natural gas to said retort, means for heating the retort 15 to raise the temperature and pressure of the mixture to a high degree, an expansion chamber in communication with the retort for the expansion of the mixture therein so as to condense and precipitate the heavier 20 constituents, means in the line of communication between the retort and expansion chamber for maintaining a predetermined pressure in the retort, and permitting flow of the mixture to the expansion chamber 25 when such pressure is exceeded, and means for separating the gas and heavy products from the lighter volatiles and condensing and collecting the latter.
2. The herein-described process of produc-

ing gasoline or other like light volatile hydrocarbon from petroleum oil or distillates, which consists in distilling a mixture of the oil or distillate with natural gas under a high temperature, whereby to raise the temperature and pressure of the mixture, causing 35 expansion of the mixture under adiabatic conditions, separating the heavier from the lighter and more volatile constituents, and then condensing and separating the vapors.

3. An apparatus for use in producing 40 gasoline or like light hydrocarbons from a petroleum oil or distillate comprising a retort, means for supplying a mixture of a petroleum oil or distillate with a predetermined quantity of natural gas to said retort, whereby to vaporize the oil and place the mixture under high temperature and pressure, means for causing expansion of the mixture under adiabatic conditions, and means for condensing and separating the 45 vapors.

In testimony whereof I affix my signature in presence of two witnesses.
